SMOKER'S PIPE WITH REMOVABLE ADJUSTABLE COVER

Frederick Hudes, Kew Gardens, N. Y.

Application August 28, 1937, Serial No. 161,374

2 Claims. (Cl. 131—176)

This invention relates to devices such as tobacco pipes.

One object of the invention is to provide a tobacco pipe having improved means for covering the pipe bowl to prevent wind from blowing burning tobacco from the bowl, and to regulate the burning of the tobacco.

I have observed that tobacco burns more readily in a pipe bowl in the presence of wind than when the atmosphere is calm. In the former case, I find that a cover is a definite aid in smoking, whereas in calm weather the cover acts as an obstruction for draft and renders it difficult to keep the pipe lit. Hence I have conceived of a removable cover, and preferably one that the smoker can readily apply and remove without requiring tools, nor any particular manipulation, and which shall afford a neat appearing pipe both with and without the cover, and yet permit the cover to be opened and closed in normal use without detachment from the pipe bowl.

It is therefore an object of the invention to provide a tobacco pipe which shall provide the advantages noted without any of the corresponding disadvantages, and in particular to provide a cover that is pivotally engageable with a pipe bowl by resilient action for easy attachment and detachment.

Another object of the invention is to furnish a tobacco pipe having a cover pivotally mounted thereon according to an improved arrangement such that a minimum of clearance space is required in swinging the cover between open and closed positions.

A further object of the invention is to provide a tobacco pipe having relatively few and simple parts, and which is inexpensive to manufacture, compact, neat, durable, reliable and efficient to a high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a perspective view of the tobacco pipe with the cover shown in closed position, and in dot dash lines in open position.

Fig. 2 is a perspective view of the tobacco pipe with the cover removed.

Fig. 3 is a vertical sectional view of the cover.

Fig. 4 is a vertical sectional view of the pipe bowl, with the cover in dot-dash lines in course of being applied thereto.

Fig. 5 is a horizontal fragmentary sectional view of the pipe bowl.

Fig. 6 is a vertical sectional fragmentary view of the tobacco pipe.

Fig. 7 is a fragmentary view in side elevation of a modified tobacco pipe.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a tobacco pipe embodying the invention. The same may include a pipe bowl 11 having an integral stem portion 12, and a detachable extension stem portion or mouth piece 13.

The pipe bowl 11 is preferably of generally circular or cylindrical shape, this being of relatively universal configuration for tobacco pipes. Opposite sides of the pipe bowl 11 are formed to provide flat parallel seating surfaces 14 for a purpose hereinafter described.

Cooperating with the pipe bowl is a cover 15 which may comprise a disc portion 16 having draft perforations 17. Depending from the disc portion are integral legs 18. The latter may have parallel inner faces 19 spaced to snugly receive therebetween the pipe bowl 11, with the faces 19 seating on those at 14. The outer surfaces of the legs 18 may be of arc shaped form to complement the outside surface of the pipe bowl to maintain a circular configuration as shown in Fig. 1, when the cover is in closed position.

To permit easy removability of the cover 15 while providing for opening and closing movement of the cover in its attached position, I provide aligned projections or tits 20 on the legs 18 at the inner faces 19. For pivotally receiving these projections, I provide depressions or recesses 21 in the opposite faces 14 of the pipe bowl.

By constructing the cover 15 of a material such as briar wood, composition, or the like, the

legs 18 are adapted to be sprung apart, so that the cover may be manipulated as shown in dot dash lines in Fig. 4 to secure the cover to the pipe bowl. The latter engages the tits or heads 20 to spring the legs apart, until the tits are received in the recesses or sockets 21. By exerting a sufficient pull on the cover 15, the tits 20 may be sprung out of the recesses 21 and the cover removed.

10 In swinging the cover 15 about the tits 20 between open and closed positions considerable clearance is required at the disc portion 16 of the cover. This necessitates a special configuration of the cover which increases the cost thereof. Furthermore, a cut away is required in the pipe bowl; as shown in Fig. 7, which, when the cover is detached, destroys the effect of regularity in the pipe bowl, and reduces the capacity thereof. I find that these drawbacks can be diminished or avoided by offsetting the recesses 21 and the tits 20 toward one side of the center of the pipe bowl, as shown in Fig. 1. A comparatively small bevel 22 will then afford all the requisite clearance while permitting the disc portion 16 to be of even thickness. In fact, the bevel at 22 affords a desirable air opening to facilitate draft.

If it be desired to reduce the stress that results in springing the cover onto the pipe bowl, as in Fig. 4, I may provide a slight bevel at each flat face 14 at the bottom thereof as shown at 23. Hence the cover 15 may be attached to the pipe bowl from the general tilted position indicated in dot dash lines in Fig. 1, by moving the cover legs 18 upward and toward the left to cause the tits 20 to pass over the bevels 23 and snap into recesses 21. This arrangement will prevent accidental upward removal of the cover, and yet, when the cover is in open position, the disc portion 16 thereof rests upon the stem portion 12 as shown, avoiding accidental release of the cover.

If the tits and their recesses be generally centrally disposed as indicated at 25 in the device 26, the bowl must be substantially cut away as at 27 and the disc part 16a of the cover must be correspondingly shaped and thickened.

These irregularities are undesirable as pointed out above. However, a bevel as at 23 may still be used.

It will thus be seen that I have provided a tobacco pipe which fulfills the objects of the invention and is well adapted for practical use, and that the invention is also applicable to pipe bowls of other contours.

I claim:

1. A tobacco pipe including a pipe bowl, a member including a cover for the bowl and legs dependingly connected to the cover, the bowl being disposed between said legs, and pivot means interengaging said legs and opposite sides of the bowl for swinging opening and closing movement of the cover about the axis of the pivot means, said member including resilient material so that the legs are adapted to be sprung apart for engagement and disengagement of the member at the pivot means, the latter including releasably interengaging head and socket portions, the sides of the bowl being beveled from the pivot means to provide cams inclined for facilitating interengagement of the head and socket portions, and the bevels being remote from the upper part of the bowl to prevent accidental upward release of the member.

2. A tobacco pipe including a pipe bowl, a one-piece member including a cover for the bowl and legs dependingly connected to the cover, the bowl being disposed between said legs, and pivot means interengaging said legs and opposite sides of the bowl for swinging opening and closing movement of the cover about the axis of the pivot means, said member consisting of briar wood so that the legs are adapted to be slightly sprung apart for engagement and disengagement of the member at the pivot means, the latter including releasably interengaging head and socket portions, and the sides of the bowl being beveled from the pivot means to provide cam inclines for facilitating interengagement of the head and socket portions without causing breakage of said member, the bevels being remote from the upper portion of the bowl so that accidental upward removal of said member is avoided.

FREDERICK HUDES.
